IRONING BOARD

Filed Jan. 9, 1928

UNITED STATES PATENT OFFICE

THOMAS E. POPE, OF SAYRE, OKLAHOMA

IRONING BOARD

Application filed January 9, 1928. Serial No. 245,604.

This invention relates to a portable ironing board, particularly, although the same may be applied to any sort of portable table, shelf, or other similar device.

5 It is an object of the invention to provide a practical means of support for a board, table or other device, and one that will be substantially rigid while the board is being used.

10 At the same time it is another object of the invention to so fold the parts together, as to permit compactness and thus conserve space while the device is not being used, and folded up out of the way.

15 On the sheet of drawing, accompanying and forming a part of this specification,

Figure 1 is a view in side elevation of an ironing board constructed in accordance with an embodiment of my invention;

20 Figure 2 is a view in rear elevation of the device as illustrated in Figure 1;

Figure 3 is a view in side elevation of the board as herein disclosed folded; and

25 Figure 4 is a view in bottom plan of the device as illustrated in Figure 3.

In the views, similar characters of reference will indicate similar parts.

The board proper is designated by 3, and to the underside thereof there are applied 30 sets of bearings 4, 5 and 6.

From the bearings 4 and 5, proceed two converging legs 7 and 8 that are properly braced at 9, 10 and 11.

35 Suitably journaled in the bearing 6 is a leg 12, dropping to a point near the floor and this leg is provided with a rest 13 to impinge upon the upper sides of the converging legs 7 and 8 when the device is set up in an operative position.

40 Secured to this leg 12 is a bearing plate 14, set in pairs on each side, and to these is pivoted a pair of straddle-legs 15 and 16, that strut out a considerable distance farther laterally than the converging legs 7 and 8, and thus providing essentially a three

point bearing for the under-supporting of the board 3, and in this way the board will not wobble, especially when the iron, for instance, is moved from side to side over the top of the board.

50 In order to hold the straddle-legs 15 and 16, in their outward position, toggle arms 17 and 18 are provided so that when they are straightening out, they will hold the legs in outward straddled position, and when the device is not in use, these toggles may be 55 folded and the straddle-legs 15 and 16 drawn in until they lay parallel with the leg 12 when the folded parts may be drawn along the underside of the leg 7 and 8 and made to 60 lay in place within the legs 7 and 8 and all the legs laying against the board 3, thus all being neatly in compact form.

Having set forth the invention, I claim:

65 An ironing table comprising a board, legs pivotally connected with the under side of said board adjacent to one end thereof, said legs being spaced apart in a direction transverse of the board, an additional leg pivotally connected to the under surface of the 70 board at a point in advance of the pivotal connections between the first named legs and the other end portion of the board, said last named leg extending between the first named legs, a member carried by the last

75 named leg for contact from above with the first named legs, when all of the legs are extended, a cross member connecting the first named legs and with which the last named leg contacts from below when the 80 legs are extended and the member carried by the last named leg is in contact with the first named legs, straddle legs pivotally connected with the last named leg at a predetermined point above its free end, toggle 85 arms interposed between and operatively engaged with the free end portion of the last named leg and the straddle legs, said toggle arms when extended limiting the straddle legs in their outward movements, said tog-

gle arms also folding to bring the straddle legs close to and substantially in parallelism with the last named leg, said last named leg having a free end spaced from the supporting surface upon which the first named legs rest.

5 In witness whereof I have hereunto set my hand this 9th day of December, in the year of our Lord, nineteen hundred and twenty-seven.

10 THOMAS E. POPE.
